DISPLAY BOX

Douglas S. Logan, Pawtucket, R. I., assignor to
 Shaw Paper Box Company, a corporation of
 Rhode Island

Application November 3, 1938, Serial No. 238,509

3 Claims. (Cl. 206—44)

This invention relates to a display box and has for one of its objects to provide an attractive display box for the merchandise contained therein, whereby the box may be displayed at an angle to, 5 or inclined, with reference to the supporting surface upon which the box may rest.

Another object of the invention is to provide a display box by which the angle of incline of the merchandise container may be varied after the 10 box is opened, whereby merchandise which may be effectively displayed at a steeper angle may be adjusted to such angle or to harmonize with the general surrounding or environment in which the display of the box may be had.

With these and other objects in view, the invention consists of certain novel features of construction, as will be more fully described, and particularly pointed out in the appended claims.

In the accompanying drawing:

Fig. 1 is a perspective view of the display box in closed position;

Fig. 2 is a perspective view of the box in open position;

Fig. 3 is a perspective view of the box adjusted 25 to a different incline;

Fig. 4 is a perspective view of the support member and body of the box alone or separate from the cover;

Fig. 5 is a perspective view of a different relative position of the body and support members;

Fig. 6 is a perspective view of the cover alone; and

Fig. 7 is a sectional view of the relative position of the parts for assembly.

It is frequently desirable that merchandise be displayed in the box in which it is housed upon opening the cover of the box, and in order that this display may be more effective I have arranged that the body of the box would be inclined with

reference to the supporting surface for the box; and, as it may frequently be desired to support the merchandise at a different angle than that to which the body may be inclined upon the opening of the cover, I have arranged that the angle

45 or incline of the body of the box be adjusted such, for instance, as by merely sliding the support member along the cover; and the following is a more detailed description of the present embodiment of this invention, illustrating the preferred 50 means by which these advantageous results may be accomplished:

With reference to the drawing, invention consists essentially of a body member 10 consisting of a bottom wall 11, opposite side walls 12—12' 55 and 13—13' which extend up from the bottom 11

and form a tray-like body, the opposite walls 12—12' and 13—13' being generally at right angles to each other and at right angles to the bottom 11. A cover designated generally 14 consists of a top wall 15 and opposite side walls 16—16' and 17—17'; the walls 16—16' and 17—17' being of distances apart to telescope over and closely fit the side walls 12—12' and 13—13' respectively of the body of the box.

A band-like support member 18 consists of opposite walls 19—19' and 20—20' in rectangular formation, forming substantially a fence-like enclosure, there being no end wall, the member 18 being frame-like and attachable to receive and have passed through it the cover 14. The walls 19—19' are substantially the distance apart of the depth of the wall 17—17' and 16—16', while the walls 20—20' are a distance apart a little greater than the walls 16—16' so as to telescopically receive these walls as illustrated in Figs. 20 1, 2 and 3 while providing that the band-like support member 18 may be slid along the cover member 14 from the position shown in Fig. 2 to the position shown in Fig. 3 when the cover is in open position.

This support member 18 is hinged to the body member 10 by a hinge 21 which is secured along the wall 19 and to the under surface of the bottom wall 11 as illustrated in Figs. 1 and 5. A tab or handle 22 may be secured to the body 10 to assist in opening the same. The support member for the body may be utilized alone in the position shown in Fig. 4 by disassembling the support member from the cover; however, when the cover is utilized it acts as a stand for adjustably supporting the member 20 therealong as shown in Fig. 3 where various inclinations of the body 10 may be had with reference to the supporting surface.

In assembly, the hinge will be attached to the support member as shown in Figs. 4 and 5 and 40 then the body moved about its hinge into the position illustrated in Fig. 7 and the cover slid into the support member 18. The relation of the parts is such that when the support member telescopes the cover, and its lower edge 23 is even 45 with the side wall 17', the body may then be swung to its closed position within the cover as the depth of the cover is such as to accommodate the portion 24 of the body which extends beyond the hinge when in this relation. This arrangement, however, would enable the support to be slid along the cover to various positions in order that the body might swing to closed position into the cover with a manipulation of the sliding sup- 50 55

2,219,034

2. In a box a body member having a bottom wall and upstanding side walls, a cover member having a top wall and downwardly extending side walls to telescope over the side walls of said body member, and a member of band-like formation extending about the top wall, opposite side walls and across the opening between said opposite side walls and slidable to different positions along said top wall and one set of opposite side walls of said cover and adapted to be positioned at different heights along said cover, said body having a portion extending into said cover and having its bottom wall hinged to the upper edge of the support along a line which is spaced from the edge of said body portion, said supporting member arranged to embrace both body and cover members when the parts are in closed position or to permit the cover to be opened to receive a portion of the body and incline the body on the support member.

5. By reason of the body extending into the cover when in open position, less space is provided at the upper edge thereof and a better appearing display is provided. If desired, some limiting means may be provided for limiting the insertion of the body into the cover. The support member's band-like form may be, and preferably will be, of a color or surface embellishment which will contrast with the remainder of the box and provide a desirable modernistic type of ornamentation therefor, while the cover also may be suitably ornamented on its inner surface to assist in the attractive display of the box.

10. The foregoing description is directed solely toward the construction illustrated, but I desire it to be understood that I reserve the privilege of resorting to all the mechanical changes to which the device is susceptible, the invention being defined and limited only by the terms of the appended claims.

I claim:

1. In a box a body member having a bottom wall and upstanding side walls, a cover member having a top wall and downwardly extending side walls to telescope over the side walls of said body member, and a member of band-like formation extending about the top wall, opposite side walls and across the opening between said opposite side walls and slidable to different positions along said top wall and one set of opposite side walls of said cover and adapted to be positioned at different heights along said cover, said body having a portion extending into said cover and having its bottom wall hinged to the upper edge of the support along a line which is spaced from the edge of said body portion, said supporting member arranged to embrace both body and cover members when the parts are in closed position or to permit the cover to be opened to receive a portion of the body and incline the body on the support member.

DOUGALD S. LOGAN.
